RALPH A. LIGHT, OF CYNWYD, AND JOSEPH W. PRICE, JR., OF PHILADELPHIA, PENNSYLVANIA, ASSIGNORS TO THE UNITED STATES METALLIC PACKING COMPANY, OF PHILADELPHIA, PENNSYLVANIA, A CORPORATION OF PENNSYLVANIA

SAND TRAP

Application filed March 24, 1932. Serial No. 600,934.

Our invention relates to the construction and mode of operation of air distributor valves used in connection with sander systems such as are used with locomotives, in which a sand trap is provided with two nozzles, one directed into the sand retaining receptacle of the trap and operating when air is forced through it to blow a supply of sand out of the trap into the delivery pipe connected with it and leading to the rails. This nozzle we will refer to as a distributing nozzle, while the second nozzle is directed into the sand delivery pipe and operates when air is delivered to it to blow out any obstructions which may have been built up in the delivery pipe. This nozzle we will refer to as the blow-out nozzle. A trap of the kind described is illustrated in our former Patent 1,800,548, granted April 14, 1931.

In the operation of traps of the kind indicated it is important that air should be directed into and through the blow-out nozzle at the beginning of a sanding operation and should be, after a short interval, cut off from this nozzle, leaving the distributing nozzle in operation. This can be accomplished in many ways and a number of automatic distributing valves have been devised, which when air is admitted to the conduit leading to the sand trap, operate to permit a short and energetic blast of air through the clean-out nozzle of the trap and then to cut off this blast. The object of our invention is to provide an automatic distributing valve of a novel and highly efficient character in which the turning on of pressure air to effect the sanding of the rails effects a reciprocatory movement of the distributing valve which controls the delivery of air to the clean-out nozzle so that this valve, which is normally closed, is first moved to open the port leading to the nozzle and then after a short interval, shifted in an opposite direction to again close the port.

The nature of our improvement will be best understood as described in connection with the drawing in which it is illustrated in what we believe to be its most effective form and in which we have shown our improved distributing valve in association with a sand

trap having the features of our prior Patent 1,800,548, and our application for patent filed May 9, 1931, Serial No. 536,172.

Figure 1 of the drawing is a vertical sectional view through the distributing valve apparatus and through the associated sand trap, and

Figure 2 is a similar view on a reduced scale of a modification of the construction shown in Fig. 1.

Referring first to the construction illustrated in Fig. 1, the sand trap proper, which with the exception of its novel combination with the distributing valve constitutes no part of our present invention, consists of a sand receptacle A, connected to receive sand from a sand box through a conduit B. From the upper part of the sand receptacle a passage C leads to a delivery opening D, to which is connected the delivery pipe leading to the rail. E indicates a delivery nozzle directed into the sand receptacle A and so designed and proportioned as to deliver a limited amount of air sufficient to stir up the sand in the receptacle and carry a portion of it through the passage C to the delivery opening and pipe D. As shown, this nozzle E is connected with a chamber E¹ formed in the casting and which chamber is also connected to a nozzle E² directed into the delivery passage of the trap and located as shown in the center of the blowout nozzle F, to be described. The chamber E¹ has leading into it a restricted passage e connected with an expansion chamber e² into which air passes through a passage e³ connected in turn with the air transmission chamber G².

As shown, the effective air transmitting capacity of the passage e is made regulable by means of a needle valve indicated at e¹. The passage e³ receives air from the air supply conduit, as shown, through the air transmission chamber of the casing G, to be described. F indicates a blow-out nozzle directed into the delivery passage of the trap and designed to direct a high pressure jet of air of considerable volume into the delivery opening and connected conduit. This blow-out nozzle connects with the port J of the transmis-

sion chamber. G is the casing of an improved air distributing valve, which, as shown, is preferably formed as an integral part of the body casting of the sand trap. This casing is divided into two chambers by a movable partition, preferably formed as a flexible diaphragm H, dividing it into an air retaining chamber G¹ and an air transmitting chamber G². This diaphragm, as shown, is seated on an annular shoulder G³, formed in the casing 5 G and clamped against this shoulder by an annular plug O, screwing into a threaded end of the casing G and having a closed outer end, as indicated at O¹. To provide a connection between the restricted passage L and the chamber G¹ in the construction illustrated the edge of the plug O is grooved, as indicated at O², in such manner that the groove will register with a perforation H² formed 10 through the edge of the diaphragm and this groove connects with the chamber G¹ through one or more passages, as indicated at O³. I is an air admission port opening into the transmission chamber G² and connected with 15 an air transmission pipe, indicated at I¹, which leads to the ordinary engineers' valve, not shown, employed for admitting and cutting off high pressure air. J is an outlet port from the transmission chamber G², which is 20 connected to the blow-out nozzle F. This port is preferably located, as shown, in a wall of the transmission chamber lying directly opposite to the movable partition or diaphragm H. e³ is a restricted passage leading 25 through the wall of the transmission chamber G² connected as shown and as heretofore described with the delivery nozzle E. L is a restricted air passage, which, as shown, 30 is formed in the wall of the casing G, connecting the port I with the air retaining chamber G¹. Any restricted connection which will place this air retaining chamber in connection with the air supply pipe would 35 serve the same purpose. M indicates a valve 40 adapted to open and close the port J. The valve is shown as having a flat face and is formed on the end of a spindle extension H¹, secured to the center of the diaphragm H. N is a spring located in the air retaining 45 chamber G¹ and arranged to exert a constant resilient pressure on the diaphragm H, tending 50 to move and hold the diaphragm and its connected valve in the position in which the valve closes the port J. It will be understood 55 that when pressure air is cut off from the distributing valve the spring N pressing against the movable partition, as shown, the diaphragm H, will move it and its attached valve in the direction to close the port J. When 60 pressure air is turned into the conduit I¹ it will enter the transmission chamber G² through the port I and will exert pressure on the diaphragm H, moving it toward the chamber G¹ and opening the valve M so that 65 the pressure air will pass freely through the 70 port J to the blow-out nozzle F. In the construction illustrated the air will pass through the restricted passage e³ and its connected conduit passages to the distributing nozzle F and to the nozzle E² but this distributing 75 nozzle and its connected passages are in practice so formed and arranged that the amount and pressure of the air delivered through the nozzle is not large, so that the bulk of the air will pass to the blow-out nozzle F after the 80 controlling valve is open. At the same time air under pressure will pass gradually through the restricted passage L into the air retaining chamber G¹. As soon as pressure air is turned into the system it begins to build 85 up pressure in the chamber G¹ and this pressure accumulates until the total pressure on the side of the partition exposed to the air retaining chamber exceeds that on the side of the partition exposed to the pressure in the air transmission chamber, whereupon the partition and its attached valve will move in a reverse direction to that in which they were originally moved, so as to seat the valve M on the port J and shut off the delivery of air to 90 the blow-out nozzle F. Obviously, when the supply of pressure air is cut off the diaphragm and valve will remain in the position in which the valve is seated and the pressure air in the air retaining chamber G¹ will escape through the restricted passage L, so that 95 very soon the pressure on both sides of the diaphragm will be only that of the atmosphere and thus the apparatus will be in position to operate again on the admission of pressure air to the transmission chamber. 100

The provision of the restricted passage e³ leading to the distributing nozzle E as located in the wall of the air transmission chamber G², is of obvious convenience and utility 105 in a structure such as is shown in the drawing, in which the valve casing G is formed integral with the main body casting of the trap.

The modification illustrated in Fig. 2, is 110 in substance the simple substitution of a piston for the diaphragm shown in Fig. 1. A portion of the casing G is made cylindrical, as indicated at G⁴, and in place of the diaphragm in Fig. 1, a piston P is provided. A 115 hollow stem P¹ connects the piston with the valve M. The bottom of the hollow stem, indicated at P², serves as a seat for the spring n, the other end of which is held in a seat o¹ formed in the cap or cover o, which screws 120 into the threaded end of the casing G. In place of the restricted passage L, Fig. 1, we provide in the construction of Fig. 2, a restricted passage l opening, as shown, through 125 the threaded portion of the end of the casing G, as shown at l¹ and an opening l² is formed through the wall of the cap o which registers with the opening l¹ when the cap is screwed into place so that air can pass freely 130 into the chamber G¹ of the casing. It will

be obvious that the modified construction of Fig. 2 will function in substantially the same way as does the construction of Fig. 1, although it involves a certain amount of frictional resistance to the movement of the piston, which is avoided in the construction employing a diaphragm, as illustrated in Fig. 1.

In all sander systems in which provision is made for the cleaning out of the delivery pipe by means of an energetic blast of air, it is very important that the delivery of high pressure air to the blow-out nozzle should take place only during a very short period of time, as otherwise the pressure of air in the air reservoir may fall to an unpermissible amount. At the same time it is obviously desirable that when air is admitted to the blow-out nozzle it should be at high pressure so as to secure the maximum velocity and volume of the jet of air directed into the delivery pipe. It is, therefore, desirable that the valve controlling the delivery of air to the blow-out nozzle should remain closed until the pressure in the air conduit leading to the trap has time to build up; that the valve should then promptly open and that it should remain open only for a short period and then close with precision and certainty of operation, and it is also important that in case any breakage or disarrangement should occur in the mechanism controlling the movement of the valve that the valve should remain closed. All these considerations have been had in view by us in designing our improved mechanism.

It will be obvious that the time during which the valve M will remain open will depend to a large extent upon the effective cross sectional area of the restricted passage leading to the air retaining chamber and upon the area of the air retaining chamber and that by varying the cubic capacity of the air retaining chamber the period during which the valve will remain open can be fixed at will, that is, the larger this chamber is the longer will be the period during which the valve will remain open.

Having now described our invention, what we claim as new and desire to secure by Letters Patent, is:

1. An air distributing valve for a pneumatic sander system comprising in combination a casing divided into an air transmitting and an air retaining chamber by a movable partition, a port connectable with the air supply conduit of the system leading into the air transmission chamber, an outlet port from said air transmission chamber connected to the clean-out nozzle of a sand trap, a valve for opening and closing said outlet port operatively connected to the movable partition, resilient means tending to shift the partition to the position in which it will shift the valve to close the outlet port and a restricted air passage leading from the air retaining chamber of the casing and con-

nectable to the air supply conduit so that when pressure air is directed into the air supply conduit it will flow freely into the air transmission chamber of the casing and acting on the movable partition shift it to a position in which it will shift the valve to open the outlet port while at the same time the pressure air will flow through the restricted passage to the air retaining chamber and gradually build up pressure in said chamber to a point where in coaction with the resilient means it will shift the movable partition in the opposite direction and shift the valve to effect the closing of the outlet port.

2. Air controlled mechanism as called for in claim 1, in which the air transmission chamber of the casing is connected also with the air nozzle directed into the sand chamber of the trap.

3. Air controlled mechanism as called for in claim 1, in which the movable partition consists of a flexible diaphragm.

4. Air controlled mechanism as called for in claim 1, in which the casing is formed as an integral part of the casting of the sand trap.

5. An air distributing valve as called for in claim 1, in which the casing is formed integral with the casting of the sand trap and in which the air transmitting chamber is connected with the clean-out nozzle of the trap by a passage formed in the casting and also connected with the nozzle directed into the sand receptacle of the trap by a separate passage formed in the casting.
